DESIGN FOR A DUTCH DOLL SOUVENIR TEA BELL

Joseph Hollander, Baton Rouge, La.

Application September 12, 1941, Serial No. 103,318

Term of patent 14 years

To all whom it may concern:

Be it known that Joseph Hollander, a citizen of the United States of America, residing at Baton Rouge, in the Parish of East Baton Rouge and State of Louisiana, has invented a new, original, and ornamental Design for a Dutch Doll Souvenir Tea Bell, of which the following is a specification, reference being had to the accompanying drawing, forming part thereof.

I claim:

The ornamental design for a Dutch doll souvenir tea bell, as shown.

JOSEPH HOLLANDER.
